ACCOUNTING MACHINE

Gustav V. A. Malmros, Binghamton, N. Y., assignor to International Business Machines Corporation, New York, N. Y., a corporation of New York

Application August 14, 1935, Serial No. 36,081

1 Claim. (Cl. 235—61.6)

This case relates to card-controlled accounting machines.

The controlling record cards have columns of index points perforated according to a selected code to represent desired items. Reading the card perforations are analyzing means for each column and controlled by the analyzing means according to their readings of the perforations are adding and printing mechanisms. The adding and printing mechanisms include several banks of elements and each bank is usually connected to the analyzing means of certain card columns to be controlled by the data in the latter columns of successively fed cards. Thus, numbering the card columns 1 to 45, columns 1 to 3 of successive cards may control one bank of printing or adding elements and columns 4 to 6 control another, separate bank of printing or adding elements.

It is desired in the present case to depart from above practice by providing means to shift the control, in predetermined sequence, of a bank of printing or adding elements from one group of card columns to another of successive cards.

Thus, columns 1 and 2 of one card may control a bank #4 of elements and columns 3 and 4 of the next card control the same bank of elements. This is the general object of the present invention.

The object is further to shift the control of several banks of elements in predetermined sequence, from different groups of card columns. Thus in above example, where the first card has columns 1 and 2 controlling bank #4, columns 3 and 4 may control bank #5 and the second card which controls bank #4 by columns 3 and 4 may have its columns 1 and 2 control bank #5. This alternation in control of the two banks may continue through the run of cards.

It is also proposed to print a list of totals taken in predetermined sequence from different columns of successive cards. Thus printing bank #1 may print the addition of two items, one taken from columns 1 and 2 of one card and the other item taken from columns 3 and 4 of the next card.

Ancillary to above object is the control of the printing bank first from one accumulator bank and then from another.

The latter object also includes the sequential zeroizing of the several banks of accumulators.

Other objects will appear in the further parts of the specification and from the drawings, in which

Fig. 1a is a portion of the circuit diagram,

Fig. 1b is another portion of the circuit diagram, and

Fig. 2 is a timing chart.

For purposes of the disclosure, the record cards will be considered as perforated according to the Hollerith system in which each card column has perforation receiving positions 9, 8, 7,—0, 11 reading upwardly from the bottom of the card and in which a single perforation in a column is used to represent a value corresponding to its position in the column. Assume that items A and B are to be added and their total printed. Assume further that items A are in columns 7 and 8, which may be referred to collectively as card field A of the cards and items B are in columns 9 and 10, which may be referred to collectively as field B of the cards. Each of the series of cards except the first and last has both these items but the first card is bare of item A while the last card is bare of item B. Each card but the first also has a card number, say in columns 4 and 5. These card numbers are progressive, that is, if the second card is number 57, the third card is number 58, the fourth 59, and so on. These card numbers are used to control total taking and accumulator resetting cycles.

The invention has for purposes of the disclosure been applied to the machine described and shown in Patent No. 1,976,617.

After placing the series of cards in the machine, the operator depresses reset key R to close reset key contacts R¹ establishing the following circuit (see Fig. 1a).

Circuit A.—From line 20, through closed cam contacts P3, relay 21, line 22, key contacts R¹, closed relay contacts 23a, line 24, closed cam contacts L2, and to line 25.

Circuit A energizes relay 21 to close contacts 21a, thereby shunting key contacts R¹ out of above circuit, to maintain relay 21 energized after key R is released.

Closing of contacts 21a also forms the following circuit (Fig. 1a).

Circuit B.—From line 20, through contacts P3, closed relay contacts 26a, reset clutch magnet 27, contacts L4, relay contacts 21a, line 28, and to line 25.

Circuit B energizes clutch magnet 27 to close contacts 27a, which results in completing the following circuit (Fig. 1a).

Circuit C.—From line 20, through reset motor RM, relay 29, line 30, contacts 27a, line 31, and to line 25.

Circuit C energizes motor RM.

At this time then, motor RM will be set in

operation and clutch magnet 27 will have clutched the reset mechanism to the motor RM for a single total print and reset cycle. During this print and reset cycle, cam contacts P7 and P8 will 5 close momentarily, forming the following circuit (Fig. 1a.)

Circuit D.—From line 20, through cam contacts P7, P8, magnets 32, 33, line 34, control magnet 35, line 36, closed cam contacts L10, L9, lines 37, 10 38, and to line 25.

Circuit D energizes magnet 32 to close contacts 32a thus shunting out contacts P7 and P8 to maintain circuit D after the latter contacts open.

The operator now depresses the start key to 15 close contacts ST. Since magnet 35 has been energized by circuit D, contacts 35a are now closed and with closing of contacts ST the following circuit is established (Fig. 1a.)

Circuit E.—From line 25, through contacts 35a, 20 stop key contacts SP, start key contacts ST, magnet 23, contacts 39a, tabulating clutch magnet 39, contacts P1, and to line 20.

Circuit E energizes magnet 39 to open contacts 39a, thus causing above circuit to be completed 25 through a by-pass path E—1 including lines 40, magnet 41, and line 40'. As a result magnet 41 is energized and closes contacts 41a to form the tabulating motor circuit as follows (Fig. 1a.)

Circuit F.—From line 20, through motor TM, 30 contacts 41a, and to line 25.

Tabulating clutch magnet 39 being energized at this time due to circuit E, the motor TM is effective upon completion of circuit F to drive the various tabulating mechanisms.

35 Circuit E, when established, energized magnet 23 to close contacts 23b to by-pass start key contacts ST through a path E—2 extending from line 25 through cam contacts L2, line 24, and contacts 23b. Towards the end of the cycle, cam 40 contacts L2 break and path E—2 opens. Now with start key contacts also open, magnets 23, 39, and 41 are deenergized. Contacts 41 open and the tabulating motor TM stops.

During this first tabulating cycle, cam contacts 45 L9 and L10 open but circuit D is maintained through a by-pass path including contacts LCLa and UCLa.

Near the end of the first cycle, after cam contacts L2 open, the leading end of the first card 50 engages the upper analyzing brushes UB and upper card lever 42'. The latter engagement closes upper card lever contacts 42 which establishes the following circuit (Fig. 1a).

Circuit G.—From line 25, through contacts 42', 55 relays UCL, and to line 20.

Contacts UCLa open as a result of circuit G but by this time cam contacts L9 and L10 have re-closed to maintain circuit D operative.

At the end of the first tabulating cycle, relays 60 UCL are energized and control magnet 35 is still energized.

The operator now again depresses the start key to manually initiate a second tabulating cycle. Circuits E and F are again established and the first card is fed to the lower analyzing brushes LB while the second card is fed to the upper analyzing brushes UB.

During the second cycle, cam contacts L9 and L10 again open but at this time, relay UCL being energized contacts UCLa are opened so that circuit D is broken, resulting in deenergizing magnet 35 to open contacts 35a and permit contacts 35b to close. Later in the cycle, cam contacts L2 open to break circuit path E—2. With 75 contacts 35a open, neither circuit E or E—1

can be made. As a result, the tabulating motor TM and clutch magnet 37 are deenergized. At the end of the second cycle, the first card will be at the lower analyzing brushes LB and the second card at the upper analyzing brushes UB. 5 The lower card will have closed lower card lever contacts 43 at the end of the second cycle to form the following circuit (Fig. 1a).

Circuit H.—From line 25, through lower card lever contacts 43, line 44, relays LCL, and to 10 line 20.

After magnet 35 is deenergized during the second cycle, permitting contacts 35b to close, cam contacts L3 close to establish the following circuit (Fig. 1a). 15

Circuit J.—From line 25, through contacts 35b, switch 45, contacts L3, magnet 21, cam contacts P3, and to line 20.

Energization of magnet 21 closes contacts 21a to hold circuit J after contacts L3 open. After 20 the latter contacts open, and at the very end of the tabulating cycle, cam contacts L4 close and reset clutch magnet circuit B is reestablished, in turn re-forming reset motor circuit C. The machine now goes through a second reset cycle 25 during which contacts P7 and P8 again close to reestablish circuit D through magnet 35.

At the end of this reset cycle, cam contacts P2 close and establish a circuit E—3 from line 25, through contacts 35a, contacts SP, contacts 30 LCLb, contacts P2, switch 46, and as before in circuit E through magnets 23 and 39. Energization of magnet 39 initiates the third tabulating cycle.

During the first of above described tabulating 35 cycles, the first card will have been advanced to the upper analyzer brushes UB and will just have closed upper card lever contacts 42 to form circuit G, which energizes relays UCL.

The description thus far has treated of known 40 matter. The new matter will now be explained.

During the second tabulating cycle, as the first card passes under brushes UB, a circuit G remains in force and relays UCL remain energized. At the 11 point (see Fig. 2) of this second cycle, 45 cam contacts L48 close and the following circuit is established (Fig. 1a).

Circuit K.—From line 25, through contacts UCLd, relay 49, cam contacts L48, closed relay contacts 50a, and to line 20. 50

Circuit K energizes relay 49 to close contacts 49a and establish a shunt path K—1 through cam contacts L15, which by-passes contacts L48. The latter contacts open just before the 12 point of the cycle but relay 49 remains energized 55 through said shunt path until contacts L15 break at the 11 point of the next (third) tabulating cycle.

Consequently, when contacts L48 open, circuit K remains in force during the data analyzing 60 period 9 through 0 of the third cycle.

Concurrently with making of circuit K—1, parallel circuit K—1 are closed through magnets 52, 53, and 54 and these circuits also remain in force during said data analyzing period of the 65 third cycle.

Magnet 54, when energized, shifts a multiple number of parallel contact blades 54' to open contacts 54a and to close contacts 54b (see Fig. 1b). 70

Magnet 52, when energized, opens multiple contacts 52a (Fig. 1b).

Magnet 53 upon energization shifts blades 53' to open contacts 53a and to close contacts 53b (Fig. 1b). 75

Thus, during the third cycle, from 9 through 0, contacts 54b and 53b are closed and contacts 52a, 53a, and 54a are open. During the third cycle, the first card runs through the lower brushes LB which sense the perforations in index point positions 9 to 0 of the card to read off the data represented by the perforations. The first card of the series has only the item B punched therein, as previously explained. When the 10 brushes LB scanning card columns 9 and 10 bearing data B sense a perforation, an adding circuit is formed as follows:

Circuit L.—From line 25, through lower card lever contacts 43 and circuit breakers 55 (Fig. 15 1a), common contact member 56 of the lower analyzer—continue with Fig. 1b—brush LB engaging the common member 56 through the perforation in the card, plug socket 51, plug wire 58, plug socket 59, contacts 54b, plug socket 60, 20 line 61, plug socket 62, adding control magnet 63 of accumulator bank #4, and to line 20.

Magnets 63 when energized by circuits L cause entry of item B into accumulator #4.

At the 9 point (see Fig. 2) of the third cycle, 25 cam contacts L62 (Fig. 1a) make and a circuit is formed as follows (Fig. 1a).

Circuit M.—From line 25, through contacts LCLd—or UCLd—relay 50, contacts L62, relay contacts 49a, cam contacts L15, and to line 20.

30 Energization of relay 50 closes contacts 50b to form a by-pass path M' extending from contacts 50b, through cam contacts L63, and to line 20.

Relay 50 also opens contacts 50a of circuit K. 35 At the 11 point of the third tabulating cycle (after contacts 50a have opened), cam contacts L15 open and the circuits through magnets 49, 52, 53, and 54 open. Now when contacts L48 close at the 11 point, circuit K cannot be completed again during the latter part of the third cycle because relay 50 has already opened contacts 50a. As a result, after the analyzing period 9 to 0 of the third cycle, magnets 49, 52, 53, and 54 are deenergized.

45 At the 12 point of the third cycle, cam contacts L63 open to deenergize magnet 50, which permits contacts 50a to make but since by then contacts L48 have opened, circuit K is still unable to form.

50 During the third cycle, the second card was passing through the upper analyzer brushes UB. This second card contains perforations in columns 4 and 5 denoting a card number. This card number is used to effect minor control operations. 55 As the first card does not have a card number, there will be no agreement of minor control perforations during the third cycle and consequently at the end of this cycle, control magnet 35 will be deenergized to cause the tabulating mechanism to stop.

The minor group control is effected as follows (see Fig. 1a). The upper brushes UB reading the card number, columns 4 and 5 have their plug sockets 64 connected by plug wires to plug sockets 65 65 of control relays each having a pick up coil 66a and a holding coil 66b. Brushes LB reading card columns 4 and 5 have their plug sockets 57 connected by plug wires to plug sockets 67 of the same control relays.

70 If the perforations in the minor control columns of the upper and lower cards agree, a circuit will be formed through each perforation from line 25, through lower card lever contacts 43, circuit breakers 55, common 56 of the lower analyzer, brush LB sensing the control perfora-

tion, socket 57, wire to socket 67, pick-up winding 66a, socket 65, wire to socket 64, upper brush UB, common 68, cam contacts L11 (closed during analyzing periods) and to line 20.

75 Energization of winding 66 results in closing contacts 69 and 70. When contacts 70 close, a circuit is formed from line 20, through cam contacts L12 (closed during the analyzing period), contacts 70, holding windings 66b and to line 25.

10 Circuit D which was formed during the second automatically initiated, reset cycle following the second tabulating cycle is maintained through relay contacts 32a and cam contacts L9 and L10 during the data analyzing period of the third, 15 automatically initiated, tabulating cycle. Following the 11 point of the third cycle, cam contacts L9 and L10 open. At this time, if the minor control data had not changed, holding windings 66b would be energized and a by-pass 20 path D—1 around contacts L9, L10 would be formed from the lower blade of contacts L10, serially through the two lowest pairs of closed contacts 69, plug wire 71, contacts UCLe, to lines 25 and 25.

25 When circuit D—1 is thus made, magnet 35 stays energized and contacts 35a remain closed. Consequently, when cam contacts L2 open later in the cycle, circuit path E—2 opens but with contacts 35a closed and relays UCL energized, a 30 by-pass circuit E—3 around contacts L2 is formed as follows: From line 25, through contacts 35a, contacts SP, contacts 23c, contacts UCLb, line 24, contacts 23b, magnet 23, line 40, magnets 41 and 39 contacts PI and to line 20.

35 As in the present case, the first and second cards do not have agreeing control perforations (the card numbers), their concurrent analysis by brushes LB and UB during the third cycle does not cause the windings 66a and b to be energized 40 so that when cam contacts L9 and L10 open, by-pass path D—1 is not made and magnet 35 is de-energized. Hence, when contacts L2 open to break circuit path E—2, circuit path E—3 is also open and consequently magnets 39 and 41 are 45 deenergized causing tabulating motor circuit F to open and the tabulating mechanism to stop at the end of the third cycle.

The deenergization of magnet 35 causes a reset 50 cycle to automatically follow the end of the third tabulating cycle in the same manner as described following the second tabulating cycle. At the end of the third cycle, accumulator #4 has had entered therein item B taken from the first card of the series. Also at the end of the third cycle, 55 magnets 52, 53, and 54 are deenergized and contacts 54a, 53a, and 52a are closed. Accumulator #5 is at zero at this time.

55 When circuit C is closed to operate the resetting motor, following the third tabulating cycle, 60 magnet 29 is energized and closes contacts 29a. Consequently, the following circuit is formed through reset magnet 75—5 of accumulator #5 (see Fig. 1b).

65 *Circuit N.*—From line 25, through contacts 29a, magnet 75—5, plug socket 76, plug wire 77, the bottom pair of closed contacts 54a, plug sockets 59', plug wire 78, plug socket 79, and to line 20.

70 Thus, during the total print and resetting cycle following the tabulating cycle, resetting magnet 75—5 of accumulator #5 will be energized to cause resetting of the latter accumulator in the manner disclosed in aforementioned Patent No. 1,976,617.

Cam contacts P6 close at the beginning of the total print and resetting cycle to cause the following circuit to be made during said cycle (Fig. 1b).

Circuit O—5.—Line 20, cam contacts P6, plug connection 81, top pair of contacts 54a, plug wire 82, magnet 83—5 and to line 25.

Energization of magnet 83—5 closes contacts 83b—5 to establish the printing control circuits through the bank of printing control magnets 84—5. The printing control circuit is as follows:

Circuit P—5.—From line 25, through circuit breaker contacts 85, common segment 86 of an impulse emitter E (one for all the printing banks), brush 87 contacting the segment, arm 88, brush 89, commutator element 90, wire 91, a contact spot 92 of the read-out commutator 93—5, brush connection 94 engaging the read-out spot 92, common conductor 95, contacts 83b—5, line 96, print magnet 84—5, and to line 20.

Since there has been no entry of items yet in accumulator #5 by the end of the third tabulating cycle, this accumulator and its readout commutator will stand at 0, and circuit P—5 will not form since, as indicated in Fig. 1b, the 0 spots of the readout commutators and of the emitter E are not wired. Consequently, the type bars of accumulator #5 will move to their uppermost position and no printing will be effected since the hammers will strike a dummy block in this position of the type bars, as is well known in the art.

During the printing and reset cycle just described, contacts 54b are open. As a result, circuits O—4 and N—4 do not form. Circuit O—4 is similar to circuit O—5 except that the circuit goes through top contacts 54b and through magnet 83—4 of accumulator #4.

Circuit N—4 is similar to circuit N—5 except that the circuit goes through the lowermost pair of contacts 54b and through resetting magnet 75—4. Since resetting magnet 75—4 is not now energized, accumulator #4 retains its entry of item B.

Also since magnet 83—4 is not energized, contacts 83b—4 of printing bank #4 are not closed and circuits cannot form through printing magnets 84—4.

Following the latter printing and resetting cycle, magnet 35 is again energized and in the same manner as after the second printing and resetting cycle, a fourth tabulating cycle is automatically initiated. During this fourth tabulating cycle, the second card goes through the lower analyzer brushes LB and the third card goes through the upper analyzer brushes UB.

As previously explained, at the 11 point of the third cycle, cam contacts L15 opened to break the circuits through magnets 49, 52, 53, and 54. At the 12 point of the third cycle, cam contacts L63 broke to open the holding circuit M—1 through magnet 50. Thus, at the end of the third tabulating cycle, the magnets 49, 52, 53, 54, and 50 are all deenergized.

During the data analyzing period—9 through 0—of the fourth cycle, contacts 54a are closed. Consequently as the second card goes through the lower analyzer, adding circuit L controlled by the columns 9 and 10 bearing item B, will extend through upper contacts 54a, plug wires 61' and adding magnets 63 of accumulator #5 to enter item B of the second card in accumulator #5. Adding circuits L will also be formed under control of columns 7 and 8 of the second card bearing an item A. These circuits L will extend

through contacts 54a, plug wires 97, plug sockets 62, and add magnets 63 of accumulator #4, thus adding the item A of the second card to the

After the analyzing period 9 through 0 of the

After the analyzing period 9 through 0 of the 5 fourth tabulating cycle and at the 11 point, cam contacts L48 make and circuits K are again formed, resulting in energizing magnets 52, 53, and 54 so that contacts 54a open and contacts 54b close, contacts 53a open and contacts 53b close, 10 and contacts 52a open.

While the second card is passing, during the fourth tabulating cycle, through lower brushes LB, the third card is going through upper brushes UB. Since the card numbers of these cards do 15 not agree, the automatic control will again operate to stop the tabulating mechanism at the end of the fourth tabulating cycle and to automatically initiate a total print and reset cycle.

This time, since the top pair of contacts 54a 20 are open, circuit O—5 is not formed, magnet 83—5 is deenergized, contacts 83b—5 open, and contacts 83a—5 closed. Since contacts 83b—5 of accumulator #5 are open, circuits P—5 cannot be made through readout commutators 93 25 of bank #5. As the top pair of contacts 54b are now closed, circuit O—4 makes to energize magnet 83—4 which closes its contacts 83b—4 and opens contacts 83a—4. Closing of contacts 83b—4 forms a readout circuit under control of 30 readout commutators 93—4 of accumulator #4. The latter readout commutators are now positioned to read out the total of items A and B, respectively taken from the second and first card of the series. The readout circuit of accumulator #4 is as follows (Fig. 1b):

Circuit P—4.—Through emitter E, readout commutators 93—4, contacts 83b—4, contacts 53b (now closed due to energization of magnet 53, while contacts 53a are open), line 98, printing 40 control magnets 84—5, to line 20.

As a result of energization of magnets 84—5, printing is effected in type bank #5 of the reading taken from readout commutator 93—4 of accumulator bank #4 so that the addition of items 45 A and B taken from the second and first cards respectively is recorded under control of add bank #4 in type bank #5.

In the absence of magnet 52 and the opening of contacts 52a during the formation of the latter 50 circuits P—4, a stray circuit would be formed through contacts 83a—5 and 52a through add magnets 63 of bank #5 which would energize the latter. It is to prevent this that magnet 52 is energized to open contacts 52a during total printing under control of add bank #4.

After total printing in type bank #5 under control of add bank #4, the latter bank's zeroized since magnet 75—4 is energized by circuit N—4 which extends through contacts 54b now closed. 60 Also since contacts 54a are open, circuit N—5 does not make and reset magnet 75—5 is not energized so that accumulator #5 still retains its entry of item B taken from the second card during the fourth of the described tabulating cycles. 65

Following the total printing under control of add bank #4 and its zeroizing, the fifth tabulating cycle is automatically initiated in the same manner as explained before. At the 9 point of the fifth cycle, cam contacts L62 make to close 70 circuits M and M' which open contacts 50a. Circuits K—1 remain in effect, however, until contacts L15 open after the 0 point. Hence, analysis of the third card by the lower brushes during this fifth cycle, forms the adding circuits L 75

through contacts 84b to enter the item B into accumulator #4 and item A into accumulator #5.

The latter already contains the reading of item B taken from the second card so that at the end of the fifth tabulating cycle, accumulator #5 has the total reading of items A and B while accumulator #4 has an entry of item B.

Cam contacts L15 open after the 0 point of the fifth tabulating cycle, thus breaking circuit K—1. When contacts L48 make at 11 of the 5th cycle, contacts 50a are open so that circuit K cannot make. Hence contacts 54a, 53a, and 52a make and the conditions are now the same as at the end of the third tabulating cycle. Also at 15 the 12 point of the fifth cycle, contacts L63 open to break holding circuit M' of magnet 50.

The third and fourth cards have different card numbers causing automatic initiation of a total printing and resetting cycle following the fifth cycle. This time the conditions are the same as during the total printing and resetting cycle following the third tabulating cycle, that is total printing is effected in type bank #5 under control of readout commutators 92—5 of the total 20 of items A and B respectively entered under control of the second and third cards into accumulator #5.

Thus, during the third tabulating cycle, item B of the first card was entered in accumulator #4. 30 During the fourth cycle item A of the second card was entered in accumulator #4 while item B was entered in accumulator #5. Following the fourth cycle, the total of items A and B in accumulator #4 was printed and accumulator #4 then zero- 35 ized. During the fifth tabulating cycle, item A of the third card was entered in accumulator #5 to be added to its reading of item B of the second card while item B of the third card was entered in accumulator #5.

40 Following the fifth cycle, the total of items A and B in accumulator #5 was printed and then accumulator #5 zeroized. This alternation goes on to the end of the series of cards.

It will be noted that entry of item A into 45 accumulator #4 occurs while contacts 54a are closed and that during the same cycle after the item entering period, contacts 54a open and contacts 54b close. As a result of closure of contacts 54b, the total printing cycle which follows 50 is under control of accumulator #4. Similarly, following entry of an item A into accumulator #5, total printing is effected under control of accumulator #5. Thus, total printing occurs under control of the accumulator into which the 55 item A has last been entered. It is not desired to leave an item B standing on the other accumulator when the cards are exhausted. Accordingly, the last card of the series is not punched with an item B, but only with an item A. 60 Hence the final total printing cycle occurs under control of the accumulator into which item A of the last card has been entered following which the latter accumulator is cleared and since no item B has been entered into the other accumulator, the latter is also at zero position.

65 It will be noted, also, that during formation of printing circuits P—5, contacts 53b are open so that a shunt circuit cannot be made through line 98 and contacts 53b through the printing control magnets 84—4 of accumulator #4.

70 Listing during tabulating cycles is prevented in the manner explained in Patent No. 1,976,617. Briefly, this is done as follows:

75 During entry of items into the accumulators, contacts 83a—4 and 5 are opened to prevent

energization of magnets 84 of accumulators #4 and #5 and consequent listing of the entries. To prevent listing, magnets 83—4 and 83—5 are energized during the period of a tabulating cycle in which circuits L may be formed. The circuit for energizing magnets 83 during tabulating cycles is as follows (Fig. 1a).

Circuit Q.—From line 25, through card lever contacts 43, cam contacts P9, normally closed contacts 21b, contacts 35c (closed by magnet 35 10 during tabulating cycles), magnet 26, and to line 20.

Magnet 26 energized by above circuit closes contacts 26a to form the following circuit through magnet 83—4 (Fig. 1b).

Circuit R—4.—From line 20, through cam contacts L14 (closed during data analyzing period 9 through 0), switch 99, contacts 26a, magnet 83—4, and to line 25.

Simultaneously a circuit is formed through 20 magnet 83—5 as follows.

Circuit R—5.—Line 20, through contacts L14, switch 99, contacts 26a' (closed by magnet 26), magnet 83—5, and to line 25.

Thus during tabulating cycles, magnets 83—4 25 and 83—5 are energized to open contacts 83a—4 and 83a—5 thereby preventing energization during the tabulating cycles of the printing magnets 84—4 and 85—5.

As previously explained, at the end of each 30 tabulating cycle, in the present case, the circuit through magnet 35 is broken because of lack of agreement in the group control columns 4 and 5.

Further, magnet 21 is energized by circuits D 35 and D—1 during total print and resetting cycles. Still further, cam contacts P9 open at the very beginning of the total print and resetting cycle. Thus, during the total print and reset cycle, circuit Q is open at contacts P9, at contacts 35c 40 because of deenergization of relay 35, and at 21b because of energization of magnet 21. Magnet 26 is thus inactive during total printing so that contacts 26a and 26a' are open and neither of circuits R—4 or R—5 can be formed. This 45 leaves magnet 83—4 and 5 free to be selectively energized during the total print cycle under control of circuits O—4 and O—5.

Briefly, the described apparatus functions to alternately enter into different accumulators an 50 item taken from the same card columns of successive cards; to enter into the same accumulator during successive cycles a pair of items taken in alternation from different columns of successive cards; to total print from a single type 55 bank the total taken in alternation from a pair of accumulators and to zeroize the accumulator from which the total is taken. An example of the utility of the apparatus is in the sale of bales of cotton which are shipped to the purchaser. The 60 cotton may absorb moisture during shipment and it is desired to add a certain average moisture weight to the original weight of each bale so that the consignee may not claim an excessive weight of moisture as part of the total weight 65 of the bale at the destination. Thus the card number in card columns 4 and 5 may be the number of the bale, item A may be the original weight of the bale, and item B the average moisture weight to be added by the consignor to the 70 original weight.

The first card contains only the moisture weight, item B. The second card contains item A, which is the original weight of the bale, and also contains items B. Items B are the same 75

but items A differ. During the third described tabulating cycle, the moisture weight will be entered in accumulator #4 under control of the first card. The next tabulating cycle, item A of the second card will be entered in accumulator #4 while item B of the second card will be entered into accumulator #5. The total of items A and B in accumulator #4 will then be printed by type bank #5 followed by the clearing of accumulator #4. The second card contains the group control number which is the number of the first bale. When the total of the weight of this bale and the fixed moisture weight is printed, the number of the bale is printed alongside. (The entering of the group control numbers into an accumulator and the total printing therefrom is done in the usual manner, well understood in the art, and need not be explained herein.) The fifth tabulating cycle enters item A of the third card, representing the original weight of the second bale, into accumulator #5 while item B is again entered into accumulator #4, as during the third cycle. The total print is then effected by type bank #5 under control of adding bank #5. Thus, during the third cycle, item B was entered into accumulator #4, and during the fifth cycle the item B was again entered in the same accumulator. During the fourth cycle, item B was entered into accumulator #5 and during the sixth and so on every other cycle will again be entered into the latter accumulator.

Similarly, item A was entered into accumulator #4 during the fourth cycle and during the sixth will again be entered into accumulator #4 while item A is entered into accumulator #5 during the fifth, seventh, ninth, and so on, cycles. Also, after each entry of item A, the accumulator receiving this entry will control a total printing operation and will then be cleared. After each tabulating cycle, type bank #5 will print the total of items A and B taken, in alternation,

from accumulators #4 and #5. At the end of the operations the machine will have printed in vertical alignment a list of total weights of the bales of cotton.

Since the invention may be embodied in different forms and permits of variations within the field of mechanism skill, I wish to be limited only by the scope of the following claim.

I claim:

In a cyclically operating accounting machine including a pair of entry receiving devices and means for controlling the devices in entering operations; the combination of connecting means between said devices and the controlling means for selectively placing one or the other of the devices under control of said controlling means; a magnet for controlling said connecting means; a cyclically timed holding circuit for said magnet; an initiating circuit, including cam contacts closed each cycle and a closed switch, for initiating energization of said holding circuit; means controlled by said holding circuit, when the latter circuit is closed during a cycle, for opening said switch after said magnet has been energized; and cyclically timed means for holding said switch opening means in effective condition to maintain the switch open during the making of said cam contacts in the next cycle to prevent formation of the initiating circuit during the latter cycle and also controlling said switch opening means to permit reclosing of said switch before the cam contacts make during the cycle after the latter cycle, whereby the initiating circuit and consequently the holding circuit are closed during alternate cycles to cause the magnet to render the connecting means effective alternately to place first one and then the other of the devices under control of said controlling means.

GUSTAV V. A. MALMROS. 40
